UNITED STATES PATENT OFFICE.

CEDRIC P. SIBLEY, OF DETROIT, MICHIGAN.

MACHINE FOR FORMING AND SETTING FASTENERS FOR PAPERS AND OTHER MATERIALS.

Application filed November 1, 1922. Serial No. 598,400.

To all whom it may concern:

Be it known that I, CEDRIC P. SIBLEY, a citizen of the United States, residing at Detroit, in the county of Wayne and State of Michigan, have invented a certain new and useful Improvement in Machines for Forming and Setting Fasteners for Papers and Other Materials, of which the following is a full, clear, and exact description.

The object of this invention is to provide a machine for forming and setting fasteners for papers and other materials, and particularly adapted to forming and setting fasteners of substantially the type shown in my Patent No. 1,397,787, granted November 22, 1921, and the machine is in some respects similar to the well known "Challenge" presses represented in the patents of Edward L. Sibley No. 358,224, granted February 22, 1887, and No. 691,012, granted January 14, 1902.

The machine of this invention is distinguished from the machines of the last two patents above mentioned by the fact, among others, that it is adapted to form as well as to set fasteners, whereas the machines of the patents mentioned are designed for setting and removing fasteners merely.

The invention consists in a machine for setting fasteners for papers and other materials, comprising a base, mounted in which is an anvil movable longitudinally therein and containing a pin arranged for sliding engagement with said anvil and provided with an extension which works in an aperture in said anvil and through which said pin may be projected, a plunger carried by and slidable in an arm rising from said base and provided with a relatively movable punch member, and a cam arranged for operative engagement with said plunger and punch member, whereby a fastener may be formed and set by the cooperation of said anvil, pin, plunger and punch member; the invention being applicable alike to a hand-fed machine and an automatically fed machine, as I will proceed now to explain and finally claim.

In the accompanying drawings illustrating the invention, in the several figures of which like parts are similarly designated, Figure 1 is a side elevation, with some parts in central vertical section, showing my machine equipped for hand feed. Fig. 2 is a horizontal section taken in the plane of

line 2—2, Fig. 1, and looking in the direction of the arrows. Fig. 3 is a perspective view of the pin. Fig. 4 is a perspective view of the punch member. Fig. 5 is a side elevation of my machine equipped for automatic feed of the fastener blanks. Fig. 6 is a horizontal section taken in the plane of line 6—6 of Fig. 5, and looking in the direction of the arrows. Fig. 7 is a plan view of a strip of fastener blanks of a type suitable for use in my machine. Figs. 8, 9 and 10 show, respectively, the three setting stages, namely, forming, collapsing and clinching, of a fastener as accomplished by my machine.

Referring particularly to Figs. 1 to 4, the machine comprises a base 1, provided with a boss 2 bored as at 3 and 4 to form a two-diameter recess adapted to receive an anvil 5, maintained in proper longitudinal sliding alinement within the boss 2 by means of a pin and groove connection 5' (see Fig. 2). This anvil is provided with a shoulder 6 and a guide extension 7, the shoulder 6 abutting against a lip 8 formed by the small bore 4, and the anvil being held normally in such position by means of a stiff spring 9, having its lower end bearing against a plate 10 secured to the base, as by screws 11, or other appropriate fastening devices.

The anvil 5 has a central bore 12 to receive a pin 13 which is provided with a reduced portion 14 and an extension 15 preferably flattened as shown, this flattened extension fitting in and adapted for sliding engagement with a complementally shaped aperture 16 in the face or top of the anvil. The pin 13 is normally forced downward by a light spring 17, and its downward movement is limited by the plate 10 with which the lower end of the pin normally contacts. The anvil and pin are provided with a snap detent means comprising a transverse bore 18 in the pin in which are mounted two balls 19 normally forced apart by an interposed spring 20, and these balls are adapted for cooperation with a complemental internal circumferential groove or seat 21 in the extension 7 of the anvil, as will be herein-after pointed out. The balls 19 are prevented from escaping from the bore 18 by means of the lower portion of the extension 7 which is counterbored, as at 22, to form a seat for the balls, the counterbore being tapered inwardly at its upper end, as at 23,

to easily accomplish the forcing of the balls into the bore 18 against the pressure of the spring 20 when relative movement between the anvil and pin takes place, as will be 5 hereinafter explained. Obviously other forms of snap detent may be substituted for the form shown and described.

Downward movement of the anvil is limited by means of a stop ring 24 normally 10 embracing the lower end of the pin 13 and chamfered as at 25 to permit easy centering of the pin therein.

The upper face of the anvil is slightly dished, as at 26, for a purpose later explained, and is provided with a resilient fastener-positioning member 27 having an extension 28, which extension acts as a spacing member between the anvil and the plunger next described. The positioning member is 20 centered upon the upper face of the anvil by means of pins 29, which also act as stops for accomplishing the proper positioning of a fastener blank upon the anvil.

Rising from the base 1 is an arm 30 provided with a socket 31 in which is mounted a plunger 32 shouldered as at 33 and forced normally upward by a spring 34 interposed between the end 35 of the socket and the shoulder 33. Within this plunger is mounted 30 a punch member 36 having a lower end 36' of reduced diameter cooperating with a bore 32' of the plunger and arranged for free sliding movement within the plunger, as hereinafter described.

35 The arm 30 carries bearing members 37 between which is journaled a cam member 38 having a pair of spaced cams 39 for accomplishing the forming operation of the machine and a concentric cam 40 actuated therewith, and a cam 41 for performing the fastener setting operation of the machine, these cams being formed preferably integrally with a lever 42 and being journaled upon a pin 43.

45 The operation of this form of the invention is substantially as follows:—When it is desired to fasten together two or more pieces of paper or other material, a fastener blank, such for example as one section of the multiple blank shown in Fig. 10, is positioned upon the anvil by slipping it between the resilient positioning member 27 and the upper face of the anvil, until it abuts against the stop pins 29. Then the papers or other material to be fastened together are positioned upon the anvil, and the lever 42 is depressed backwardly, or to the right, looking at Fig. 1. This causes the spaced cams 39 to act upon the upper end of the plunger 32 and force the plunger down into contact with the paper, and further movement of the lever 42 in the same direction will cause the anvil 5 to be depressed against the spring 9. 60 As the anvil is thus depressed the reduced and flattened portion 15 of the pin 13 will

be projected through the aperture 16 in the anvil, and, coming in contact with the fastener blank, will force the blank through the paper or other material and into the bore 32' of the plunger, the punch member 36 being thereby prevented from descending with the plunger and permitting the fastener blank to be formed into a substantially tubular shank (as shown in Fig. 8) within the bore 32' of the plunger. The spacing member or extension 28 prevents breaking of the blank during the forming operation by allowing an initial small clearance between the flattened extension 15 and the edge of the bore 32' into which the blank is therefore 75 easily bent. Inasmuch as the cam 40 is concentric with the center of oscillation of the cams 39, a space will be left between the top of the punch member 36 and the face of the cam 40 as the plunger 32 descends, and it is into this space that the punch member moves as the forming operation takes place upon the fastener. As the anvil 5 descends, the

balls 19 will be forced into the bore 18 by the action of the taper 23, and continued descent of the anvil will bring the circumferential groove 21 into alignment with the bore 18, whereupon the balls will snap out of the bore and into engagement with the groove. Continued depression of the anvil will cause the balls to be forced out of the groove and back into the bore 18 again, while the anvil completes its descent to the point where it is stopped by the ring 24.

The operation of forming the fastener being completed at this point, the lever 42 is raised. This permits the spring 9 to force the anvil upward to its normal position, but the pin 13 instead of remaining in its normal downward position, as shown, will rise 100 with the anvil because of the engagement of the balls 19 with the groove 21 as the anvil rises, and the fact that the spring 17 is not of sufficient strength to counteract this engagement, the relative location of the groove 110 21 with respect to the upper end of the flattened portion 15 being such that the flattened portion 15 will extend slightly above the upper face of the anvil. It will be obvious that as the plunger 32 rises under the influence of its spring 34 as the lever 42 and cams 39 and 40 are returned to normal position, the reduced portion 36' of the punch member 36 will eject the formed fastener 115 from the bore 32' of the plunger, the retaining action of the positioning member 26 cooperating with the action of the punch member 36 to hold the fastener in proper position upon the anvil, this positioning being aided also by the aforementioned projection of the flattened portion 15 of the pin extending into the formed fastener. The setting of the fastener must now be accomplished. This is done by moving the lever 42 forwardly (or to the left in Fig. 120 125 130

1). This movement brings the cam 41 into play, and inasmuch as this cam in addition to acting upon the top of the plunger 32 acts also upon the top of the punch member 36, the plunger and punch member are moved downward simultaneously, presenting an unbroken setting surface on the lower end of the plunger to the top of the formed fastener. The continued downward movement of the plunger will deform the fastener (as shown in Fig. 9), and will finally flatten it out to full clinched or set position (as shown in Fig. 10), the anvil in the meantime remaining in its upward position by virtue of the fact that its spring 9 is of such strength as to withstand that amount of pressure necessary to deform and clinch or set the fastener. Here again the slight projection of the flattened portion 15 of the pin 13 comes into play, in that when the fastener is being collapsed this projection of the flattened portion inside the fastener prevents its collapsing inwardly. Here also the dishing of the face of the anvil surrounding the flattened portion of the pin is operative in preventing spreading of the fastener adjacent to the flattened portion as setting pressure is applied. During this setting or clinching operation the spring retained anvil will act as a cushion, thereby insuring even compression upon the fastener.

Referring to Figs. 5 and 6 of the drawings, wherein an automatic device for feeding a strip of fastener blanks such as illustrated in Fig. 7, is shown, it is to be understood that all of the parts of the machine relating essentially to the forming and setting of the fasteners are identical with those shown in Fig. 1, excepting in so far as their proportions and formation are modified to accommodate the automatic feed mechanism.

This automatic feed mechanism comprises a plate 44 adapted to be mounted upon the top of the anvil 5 and having side flanges or guides 45 and a downturned lip 46, and above this plate 44 and spaced from it by washers 47 is another plate 48 corresponding in essential features with the resilient positioning member 26 of the hand feed machine previously described, but having rearwardly extending arms 49. Screws 50 pass through the plate 48, washers 47 and plate 44 to hold the plates 44 and 48 in proper relative arrangement upon the anvil. The plates 44 and 48 together constitute a guide for a strip of fastener blanks. As will be seen by reference to Fig. 6, the plate 48 is not as wide as the plate 44, thereby providing slots or guideways 51 between the edges of the plate 48 and the side flanges 45 of plate 44, and in these guideways 51 slide feed dogs or arms 52 extending rearwardly from the anvil and pivoted by means of slotted openings 53 in their extremities upon a pin 54 mounted between and carried by the spaced arms 55

which take the place of the arm 30 of the form of the machine shown in Figs. 1 and 2, the pin 54 being provided with a sleeve 56 adapted to space the dogs 52 in proper alignment with the guideways 51. These dogs are normally forced forwardly and toward the anvil by means of springs 57, the free ends 58 of which abut against lugs 59 formed on the arms 55.

The operation of this form of the invention in so far as the forming and setting of the fastener are concerned, is identical with the hereinabove described operation of the form of the invention shown in Figs. 1 and 2, and in order that the operation of the automatic feed mechanism may be understood, it will be necessary only to describe the operation of same in connection with the forming and setting operations of the other parts generally.

The strip of fastener blanks shown in Fig. 7 is fed into the machine from the back between the arms 55 and resting upon the inclined surface 60, and its leading end is inserted between the lip 46 and the arms 49 so that it is fed between the plates 44 and 48 to the anvil. The feed arms 52 are then retracted and their leading ends positioned behind the edges 61 of a fastener blank of the strip, thus forcing the leading blank of the strip forward upon the anvil until its leading edge abuts against the washers 47, thereby being held in proper relative position to the forming and setting mechanism. Now, upon the insertion of the material upon which the fastener is to be set, and the depression of the lever 42 for the forming operation, the descent of the anvil and the projection therethrough of the flattened portion 15 of the pin 13 will shear off the fastener blank which is in forming position from the strip of blanks, and will form it into a fastener in the manner previously described. In this connection the extension 62 of the plate 48 will function, in that as the plunger descends its descent will be limited by the extension 62, and as the flattened portion 15 of the pin 13 rises, the shearing operation of the portion 15 acting in conjunction with the extension 62 and the plunger and the bore 32' thereof will sever the blank from the strip of blanks and will form it into a fastener as hereinbefore described, the slight space between the blank being formed and the plunger, caused by the projection 62, serving to prevent cutting in half of the blank and facilitating its bending within the bore 32' into fastener form.

As the plunger descends and forms the fastener from the blank, the anvil also descends, as previously described, and the pressure between the plunger and anvil and the continued interposition of the fastener being formed between the washers 47 and the remainder of the fastener blank will prevent

4. a new blank from coming forward into position for forming, and while the anvil descends the feed arms 52 will drop back behind the next adjacent fastener blank for the reason that it is impossible for these arms to move forward any farther than is allowed by the length of the slot 53. Now, when the fastener forming operation is completed, and the anvil rises, the springs 57 will have a tendency to force the next blank into forming position and to force the already formed fastener out of setting position, but this is prevented by reason of the fact that the flattened extension 15 of the pin 13 remains projecting above the surface of the anvil and acts as a stop to prevent forward movement of the strip of fastener blanks the arms 52 in consequence being forced back by the strip of blanks as is permitted by the slots 53. After the setting operation has been accomplished as described in connection with the description of the form of the invention of Fig. 1, and the material with the fastener set thereon is removed, the springs 57 will advance the arms 52 so as to position a fresh fastener blank beneath the plunger.

As shown and described, the machine is adapted for forming and setting a fastener having a flat shank, but it is obvious that by changing the form of the blank and the shape of the extension 15 of the pin 13, and its corresponding aperture in the anvil, other shapes of fasteners may be formed and set equally well. That is, by complementally changing the shapes of the forming members of the machine fasteners having cylindrical, polygonal or other shaped shanks may be formed and set with my machine.

5. It is to be understood that although I have herein shown and described a particular embodiment of my invention and have mentioned changes which may be made therein, I do not consider my invention as limited to this disclosure, but contemplate the making of various other changes in construction and arrangement of parts without departing from the spirit of the invention or the scope of the following claims.

6. What I claim is:—

1. In a machine for forming and setting fasteners for papers and other materials, a base, an anvil mounted for longitudinal sliding movement therein, means for limiting such movement, a spring normally forcing said anvil outwardly with respect to said base, a pin slidable longitudinally of said anvil, and means for locking said anvil and pin against relative sliding movement.

2. In a machine for forming and setting fasteners for papers and other materials, a base, an anvil arranged for limited sliding movement within said base, means for normally projecting said anvil outwardly with respect to said base, a pin slidable within

said anvil and provided with an extension, means defining an aperture in the face of said anvil with which aperture said extension cooperates, means for normally retaining said pin with its extension within the plane of the face of said anvil, a plunger provided with a bore and arranged for operative movement toward said anvil, and means for effecting the movement of said plunger, whereby when a fastener blank is positioned on said anvil and said plunger moved into operative engagement therewith said extension will be projected by relative movement between said pin and anvil and by cooperation with the bore of said plunger will shape said blank into fastener form.

3. In a machine for forming and setting fasteners for papers and other materials, a base, an anvil mounted for limited resilient sliding movement therein and provided with an apertured face, a pin slidable within said anvil and having an extension cooperating with said aperture, a centrally bored plunger movable for cooperative engagement with said anvil, means for imparting movement to said plunger whereby relative movement between said anvil and pin is attained and said extension projected through said aperture, and means for retaining said extension in partly projected position with respect to the face of said anvil.

4. A machine for forming and setting fasteners for papers and other materials, as claimed in claim 3, in which the partly projected position of said extension is maintained by virtue of cooperating means in said pin and anvil.

5. A machine for forming and setting fasteners for papers and other materials, as claimed in claim 3, in which the partly projected position of said extension is temporarily maintained by virtue of snap-detent means cooperating between said pin and anvil.

6. A machine for forming and setting fasteners for papers and other materials, as claimed in claim 3, in which the partly projected position of said extension is temporarily maintained by virtue of a ball and groove snap-detent means cooperating between said pin and anvil.

7. A machine for forming and setting fasteners for papers and other materials, as claimed in claim 3, in which the partly projected position of said extension is temporarily maintained by means of a spring-pressed ball carried by said pin and engaging a seat in said anvil.

8. In a machine for forming and setting fasteners for papers and other materials, a base, an anvil mounted for longitudinal sliding movement therein, means for limiting such movement, a spring normally forcing said anvil outwardly with respect to said base, a pin slidable within

to said base, a pin slidably longitudinally within said anvil, a spring normally forcing said pin inwardly with respect to said base, and cooperating means on said pin and 5 anvil for locking same against relative movement against the pressure of said pin-forcing spring.

9. In a machine for forming and setting fasteners for papers and other materials, a 10 base bored to receive a longitudinally sliding anvil, a spring normally forcing said anvil outward with respect to said base, means for limiting the outward movement of said anvil against the action of said 15 spring, means adapted to move said anvil inwardly against the pressure of said spring, means for limiting such inward movement, a pin slidably longitudinally within said anvil, a spring normally forcing said pin 20 inwardly with respect to said base, and a spring detent mechanism cooperating between said pin and anvil for locking said pin and anvil against relative sliding movement against the action of said pin-forcing 25 spring.

10. In a machine for forming and setting fasteners for papers and other materials, a base bored to receive a longitudinally sliding anvil, a shoulder on said anvil, a lip in 30 said bore, a spring abutting against said shoulder and normally forcing said shoulder against said lip, and a stop ring in said base, said lip and stop ring limiting the outward and inward movements of said anvil re- 35 spectively.

11. In a machine for forming and setting fasteners for papers and other materials, a base bored to receive a longitudinally sliding anvil, a guide extension on said anvil terminating outwardly in a shoulder, a lip in the bore of said base, a spring surrounding said extension and normally forcing said shoulder outwardly against said lip, means for moving said anvil inwardly against the 40 pressure of said spring, a stop ring adapted to cooperate with the inner end of said extension to limit the inward movement of said anvil, and a pin slidable within said anvil, said stop ring adapted to center said 45 pin.

12. In a machine for forming and setting fasteners for papers and other materials, an apertured anvil adapted to receive a fastener blank, a pin a portion of which is adapted 50 to be projected through the aperture of said anvil, a bored plunger mounted for sliding movement toward said anvil and having a punch member mounted for relative sliding movement within said bore, means for 55 moving said plunger into operative engagement with said fastener blank to project said extension and form a fastener from said blank, and means for moving said plunger and with it said punch member to set said 60 fastener.

13. In a machine for forming and setting fasteners for papers and other materials, an apertured anvil adapted to receive a fastener blank, a pin a portion of which is adapted to be projected through the aperture of said 70 anvil, a bored plunger mounted for sliding movement toward said anvil and having a punch member mounted for relative sliding movement within said bore, means for moving said plunger into operative engagement with said fastener blank to project said extension and form a fastener from said blank, and means for moving said plunger and with it said punch member to set said 75 fastener, said anvil during the operation of setting the fastener acting as a cushion.

14. In a machine for forming and setting fasteners for papers and other materials, an anvil, adapted to receive a fastener blank, and a positioning member carried by said 80 anvil and adapted to hold the blank in forming and setting position thereon during the operation of the machine.

15. In a machine for forming and setting fasteners for papers and other materials, an 90 anvil, a plunger, means for moving said plunger toward said anvil, a positioning member carried by said anvil and arranged to hold a fastener blank in predetermined fastener forming and setting position there- 95 on, said positioning member provided with a spacing member adapted to prevent direct contact between said plunger and blank and possible cutting of the blank during the fastener forming movement of the plunger. 100

16. In a machine for forming and setting fasteners for papers and other materials, an anvil and a plunger adapted by separate operations to form and set a fastener between them, and a double cam adapted to impart 105 motion to said plunger to effect said operations.

17. In a machine for forming and setting fasteners for papers and other materials, an anvil, a plunger movable relative thereto, a punch member carried by and movable relative to said plunger, a cam adapted to impart motion to said plunger independently of said punch member, a cam adapted to impart motion to said plunger and punch member 110 simultaneously, a common pivot for said cams, and a cam face concentric with said pivot and upon which said punch member may ride during the action of the plunger operating cam. 115

18. In a machine for forming and setting fasteners for papers and other materials, a movable anvil, a plunger, means for actuating said plunger to move said anvil, a guide carried by said anvil and adapted to receive 120 and guide a plurality of fastener blanks, and a spring-actuated blank feeding arm carried by a stationary part of said machine and directly engaging said blanks and adapted upon relative movement between 125 130

said mechanism and anvil to automatically feed fastener blanks between said anvil and plunger.

19. In a machine for forming and setting fasteners for papers and other materials, a movable anvil, a plunger, means for actuating said plunger to move said anvil, a guide carried by said anvil and arranged to receive and guide a strip of fastener blanks, a feed arm pivoted to a stationary part of the machine and arranged for limited sliding movement on its pivot, and means for imparting sliding movement to said arm upon movement of said anvil.

20. In a machine for forming and setting fasteners for papers and other materials, a movable anvil, a plunger, means for actuating said plunger to move said anvil, a guide carried by said anvil and arranged to receive and guide a strip of fastener blanks, a feed arm pivoted to a stationary part of the machine and arranged for limited sliding movement on its pivot, and a spring connected with said arm and bearing against the stationary part of the machine for imparting

sliding movement to said arm upon movement of said anvil.

21. In a machine for forming and setting fasteners for papers and other materials, a movable anvil, a plunger, means for actuating said plunger to move said anvil, a guide carried by said anvil and arranged to receive and guide a strip of fastener blanks, a pair of feed arms pivoted to a stationary part of the machine and slotted for limited sliding movement upon their pivots, and springs connected with said arms and bearing against the stationary part of the machine, said arms provided with means for successively engaging separate fastener blanks of said strip upon relative movement between them and said anvil.

In testimony whereof I have hereunto set my hand this thirtieth day of October, A. D. 1922.

CEDRIC P. SIBLEY.
